UNITED STATES PATENT OFFICE.

FRANK B. MILLER, OF NORWALK, OHIO.

EARTH-ANCHOR.

963,791.

Specification of Letters Patent. Patented July 12, 1910.

Application filed January 22, 1910. Serial No. 539,611.

To all whom it may concern:

Be it known that I, FRANK B. MILLER, a citizen of the United States, and resident of Norwalk, in the county of Huron and State of Ohio, have invented certain new and useful Improvements in Earth-Anchors, of which I hereby declare the following to be a full, clear, and exact description, such as will enable others skilled in the art to which

10 it appertains to make and use the same.

The objects of the invention are to provide an expansible retaining anchor for telegraph, telephone and electric trolley wire supports, or poles, the primary improvement therein having reference to the positive and powerful mechanism employed to expand or laterally elongate the same.

15 The invention is designed for use in the bottom of a hole dug in the earth, and the expansible portion of the anchor is adapted to be extended laterally beyond the sides of the hole and thereby to take advantage of the weight of the solid earth above its expanded edges.

20 25 The device is used in connection with a straining rod or draw bar to which a straining or tension rope is attached which connects the draw bar with the pole and needs no further description herein.

30 35 The invention comprises a central body and stem and laterally movable members and instrumentalities for giving a direct and positive movement to said members, which is equally powerful throughout all portions of the movement.

35 The device is hereinafter further described, shown in the accompanying drawings and specifically pointed out in the claims.

40 45 In the accompanying drawings Figure 1 is a side elevation of the device; Fig. 2 is a plan view thereof showing the laterally movable members extended; Fig. 3 is an end elevation, showing the slots and grooves adapted for the reception of working parts; Fig. 4 is a perspective view of one of the laterally movable members showing the operating rack therefor, and Fig. 5 is a perspective view of one form of wrench adapted 50 to operate the device.

In these views 1 is a preferably circular or disk shaped base plate in which is loosely secured the lower end of the draw bar, 2. Upon this base rests the laterally movable anchor members or flukes 3, 3', which slide 55 upon the body portion 1 and are radially slotted at 4, 4, to receive the draw bar 2.

Upon the lower surface of each anchor fluke is shown a lug 5 which is adapted to enter the diametrical slot 6, in the base portion 1, and guides the anchor members as they are moved in and out upon the base portion which is designed to remain stationary in the bottom of the hole. To operate the anchor members 3, 3', a disk 7 is secured to the draw bar 2, and upon the underside of this is shown a vertical spiral or cam shaped flange 8 which is adapted to engage the rack teeth 9, 9, upon the upper surfaces of the anchor members 3, 3', and draw them 70 in and out simultaneously in opposite directions as the disk 7 is rotated. This may be accomplished by means of any suitable wrench such as shown at 10 in Fig. 5, and the prime feature of advantage gained is 75 found in the positive movement resulting from the action of the spiral flange, since the anchor members are moved with equal power at all times. The anchor members are preferably duplicates and two in number but 80 any number suitably spaced can be employed. A shoulder or thimble such as "a" upon the rod 2 prevents the retaining nut N at the lower end of the rod from binding upon the parts so as to prevent movement 85 thereof.

Having described the invention, what I claim as new and desire to secure by Letters Patent is:—

1. In an earth anchor, a base plate, a draw 90 bar loosely connected therewith, a pair of anchor members or flukes, diametrically and laterally movable on said base plate, a rack on each anchor member, and a spiral engaging device for said racks, said spiral engaging device operatively connected with said draw bar.

2. In an earth anchor, in combination, a base plate, a draw bar, loosely connected therewith, diametrically movable anchor, 100

members or flukes slidingly mounted upon said base plate, said base plate provided with a guiding means operatively connected with a corresponding guiding means in said 5 anchor members, a radial rack on each anchor member, a spiral engaging device therefor, whereby said anchor members are simultaneously moved in opposite directions,

10 said spiral engaging device operatively connected with said draw bar.

In testimony whereof, I hereunto set my hand this 4th day of December 1909.

FRANK B. MILLER.
In presence of—
EDGAR L. MARTIN,
C. P. VENUS.
